UNITED STATES PATENT OFFICE.

JOHN H. McGHAN, OF BAKER CITY, OREGON.

PLANE.

No. 796,001.

Specification of Letters Patent.

Patented Aug. 1, 1905.

Application filed August 17, 1904. Serial No. 221,138.

To all whom it may concern:

Be it known that I, JOHN H. McGHAN, a citizen of the United States, residing at Baker City, in the county of Baker, State of Oregon, have invented certain new and useful Improvements in Planes; and I do hereby declare the following to be a full, clear, and exact description of the invention, such as will enable others skilled in the art to which it appertains to make and use the same.

This invention relates to planes, and more particularly to rabbeting-planes, and has for its object to provide a device of this nature which will be cheap of manufacture and simple of construction and which will be so arranged that the handle may be shifted laterally to bring it in such position that the hand of the operator will not come into contact with the edge of the rabbet as it is being cut.

A further object is to provide a construction in which the shavings will be split longitudinally, thus preventing clogging of the plane.

Other objects and advantages will be apparent from the following description, and it will be understood that modifications of the specific construction shown may be made and any suitable materials may be used without departing from the spirit of the invention.

In the drawings forming a portion of this specification, and in which like numerals of reference indicate similar parts in the several views, Figure 1 is a side elevation of a rabbeting-plane embodying the present invention. Fig. 2 is a longitudinal section of Fig. 1. Fig. 3 is a top plan view. Fig. 4 is a bottom plan view.

Referring now to the drawings, there is shown a rabbeting-plane 5, including the shoe 6 and side plates 7. Formed transversely through the shoe is the usual bit-slot 8, through which projects the bit 9, and communicating with the slot 8 is a forwardly-extending longitudinal slot 10, in which is disposed the lower sharpened end 11 of a supplemental bit 12, having a threaded stem with which is engaged a circular thumb-nut 13, one edge of which is disposed in a slot 14 in the front solid portion 15 of the plane, the bit 12 and the remainder of the nut lying within the recess 16, which communicates with the bit-slot 8. The nut 13 may thus be operated by the finger to cause the sharpened end 11 of the bit to project through the slot 10 to a greater or less degree.

Formed in the shoe 6 rearwardly of the bit

9 is a threaded recess 17, and disposed upon the upper face of the shoe is a handle 18, having a forwardly-projecting perforated nose 19 lying with its perforation in alinement with the recess 17 for the reception of a machine-screw 20, which may be loosened in the recess to permit of pivotal movement of the handle thereupon or tightened to hold the handle at any point of its pivotal movement. It will thus be apparent that the handle 18 may be swung laterally in either direction to suit the conditions under which the plane is being used and that the bit 12 when the plane is in use will split the shavings as mentioned above to prevent clogging of the plane. It will of course be understood that the bit 12 is adjusted to suit the position of the bit 9.

The plane, as will be readily apparent, may be manufactured at an extremely low cost in view of the fact that the parts are few in number and may be produced with a minimum of labor. The body portion of the plane, which includes the shoe 6 and side plates 7, may be cast integrally, and the several slots and recesses afterward formed therein. The bit 12 may be formed of bar metal flattened and sharpened at one end, as shown. The handle 18 consists of a metallic base portion 21, having the nose 19 formed thereon and having a recess 22 in its upper face which receives the lower end of the wooden grip 23, this grip being held in position by means of a screw 24, passing through a longitudinal perforation therein and engaged in a threaded perforation 25 in the base portion.

By reason of the fact that the slot 11 communicates with the slot 8 the shaving is scored practically at the same time that it is cut, so that the board is not marred beyond the portion planed.

What is claimed is—

1. In a plane the combination with a shoe having a bit-receiving slot and having a slot extending at right angles to the bit-receiving slot forwardly therefrom and communicating therewith, of a plane-bit disposed to project through the bit-receiving slot, and a scoring-bit disposed to project through the second-named slot.

2. As an article of manufacture a plane comprising a cast shoe having a transverse slot formed therein and having an upwardly and rearwardly inclined bit, a supporting member formed thereupon rearwardly of the slot, said shoe having an upwardly-extending projection formed thereupon forwardly of the slot,

said projection having a forwardly-inclined passage therethrough and through the shoe and communicating with the forward edge of the slot centrally thereof, said projection also having a slot in its rearward face extending at right angles to the passage and therebeyond in all directions, a bit connected with the bit-supporting member and projecting through the slot of the shoe, a second bit disposed in the passage of the forwardly-inclined projection and having its upper portion threaded, a thumb-nut disposed in the slot of the projec-

tion and in which the threaded portion of the bit is engaged, said thumb-nut extending outwardly of the slot and being adapted for operation to move the second-named bit into and out of position to project beneath the shoe, and a handle connected with the shoe.

In testimony whereof I affix my signature in presence of two witnesses.

JOHN H. McGHAN.
